A CORPORATION OF MASSACHUSETTS

APPARATUS FOR BLEACHING FABRIC

Application filed November 1, 1930. Serial No. 492,814.

This invention relates to apparatus for bleaching fabric in full width, open form and is particularly adapted for use in carrying out my improved bleaching process disclosed in my co-pending application filed November 1, 1930, Serial No. 492,815.

The primary object of the invention is to provide, in a manner as hereinafter set forth, an apparatus of the character aforesaid by 10 means of which fabric may be bleached without stretching or distorting the same, whereby the fabric retains its original shape during the treatment thereof, thereby eliminating the necessity of tentering the fabric and 15 further eliminating the probability of shrinkage of the finished article.

A further object of the invention is to provide an apparatus of the character aforesaid which requires a minimum of floor space, and 20 the cost of which is small in comparison with the usual bleaching apparatus.

A further object of the invention is to provide an apparatus for the purpose aforesaid, by means of which fabric may be completely 25 treated without removing the same from the apparatus, whereby the usual time necessary for the complete treatment of the fabric may be materially reduced, and whereby relatively small quantities of the fabric may be 30 treated at the same ratio of expense as larger quantities.

With the foregoing and other objects in view, the invention consists of the novel construction, combination and arrangement of 35 parts as hereinafter more particularly described, and as illustrated in the accompanying drawings wherein is shown an embodiment of the invention, but it is to be understood that the description and drawings are 40 to be taken as illustrative and that the invention is intended to be limited only by the scope of the claims hereunto appended.

In the accompanying drawings in which 45 like numerals are employed to designate like parts throughout the several views:

Figure 1 is a side elevation of an apparatus in accordance with this invention.

Figure 2 is a top plan thereof with the 50 liquor supply tank removed.

Figure 3 is an end elevation showing one of the fabric receiving vats in section.

Figure 4 is a longitudinal vertical section through the apparatus with the liquor supply tank and fabric receiving vats removed. 55

Figure 5 is an enlarged fragmentary sectional elevation showing one of the automatic clutches employed in connection with the upper carrier rolls.

Figure 6 is a section taken on a line 6—6 60 of Figure 5.

Figure 7 is an enlarged fragmentary sectional elevation showing one of the clutches employed in connection with the guide rolls.

Figure 8 is an enlarged fragmentary sectional plan showing the three-way valve employed in the liquor conduit. 65

Referring to the drawings in detail, the numeral 1 indicates a pair of upright supporting posts, upon the upper ends of which 70 are supported a pair of horizontal beams 2 extending in parallel relation. Extending between the posts 1 and projecting beyond the ends of the beams 2 is a tank 3 which is provided centrally thereof with a transverse 75 partition 4 by means of which the tank is divided into a pair of fabric receiving vats 5 and 6.

Mounted on the beams 2, centrally thereof, are a pair of slotted bearings 7 which support 80 the shafts 8 and 9 for a pair of combined feed and squeeze rolls 10 and 11 respectively. The shaft 8 is stationary except for its rotating movement, while the shaft 9 is vertically movable in order that the roll 11 may be adjusted with respect to the roll 10. The shaft 9 is journaled at its ends in a pair of blocks 12 which are vertically slidable within the slotted bearings 7. Extending upwardly from the blocks 12 are threaded rods 13 which are 85 threaded through stationary blocks 14 at the upper ends of the bearings 7, and which are provided at their extreme upper ends with hand wheels 15 for rotating the same. Power is transmitted to the apparatus through the 90 shaft 8 which is provided at one end with a pulley 16 adapted to be engaged by any suitable reversible belt, not shown.

Mounted on the beams 2, adjacent the forward ends of the latter, are a pair of bearings 95

17 in which are journaled end portions of a shaft 18 having what will be termed an upper carrier roll 19 fixedly secured thereon. Mounted on the beams 2, adjacent the rearward ends thereof, are a pair of bearings 20 similar to the bearings 17 and having journaled therein end portions of a shaft 21 having an upper carrier roll 22 fixedly secured thereon.

10 The shaft 18 is provided with an automatic clutch indicated generally at 23 and including a disc 24 having a hub 25 slidably and non-rotatably mounted on the shaft, the disc 24 further having a flange 26 formed adjacent 15 the periphery thereof. Rotatably mounted on the hub 25 is an actuating member 27 which is formed with a concentric projection 28 rotatably mounted on the shaft 18. Fixedly mounted on the projection 28 is a 20 sprocket 29. The member 27 is formed in its peripheral face with a plurality of spaced notches 30 within each of which is disposed a ball 31. The walls of the notches 30 are inclined in such a manner that the balls 31 will 25 be thrown outwardly against the inner face of the flange 26 upon the rotation of the member 27 in one direction in order that the disc 24 and shaft 18 may be rotated with the member 27 in such direction. Upon the rotation 30 of the member 27 in the opposite direction, the balls 31 fall inwardly within the notches 30 in order that the member 27 may rotate independently of the disc 24 and shaft 18. The member 27, disc 24 and shaft 18 will be rotated in unison upon the rotation of the member 27 in a counter-clockwise direction 35 as viewed in Figure 6.

The shaft 21 is provided with a clutch element 32 which will not be specifically described, the clutch element 32 being identical with the clutch element 23 except that the walls of the notches forming a part of the clutch element 32 are oppositely inclined with respect to the walls of the notches forming 40 a part of the clutch element 23. The clutch element 32 includes a sprocket 33 similar to the sprocket 29.

Extending around the sprockets 29 and 33 is an endless chain 34 which further extends 50 around a sprocket 35 fixedly mounted on the power shaft 8. The chain 34 further passes over a pair of idler sprockets 36 and 37 respectively mounted on brackets 38 and 39. Upon the rotation of the chain 34 in a clockwise direction as viewed in Figure 1, the shaft 18 will be rotated by the clutch element 23, and upon rotation of the chain 34 in a counter-clockwise direction as viewed in Figure 1, the shaft 21 will be rotated by the 55 clutch elements 32.

Mounted on the beams 2 between the bearings 7 and 17 are a pair of bearings 40 through which rotatably extends a shaft 41 having a guide roller 42 rotatably mounted 60 thereon. Rotatably and non-slidably mount-

ed on the shaft 41 is a sprocket 43 provided on one side thereof with a clutch face 44. Slidably and non-rotatably mounted on the shaft 41 is a clutch member 45 which is engaged by a shifting yoke 46 pivotally mounted on one of the beams 2. When the clutch member 45 is in engagement with the clutch face 44, the shaft 41 will be rotated with the sprocket 43, and when the clutch member 45 is out of engagement with the clutch face 44, the sprocket 43 will be rotated independently of the shaft 41.

Mounted on the beams 2 between the bearings 7 and 20 are a pair of bearings 47 through which rotatably extends a shaft 48 having a guide roller 49 rotatably mounted thereon. The shaft 48 is provided with a sprocket 50 similar to the sprocket 43, and with a clutch member 51 similar to the clutch member 45, the clutch member 51 being shiftable by means of a shifting yoke 52 similar to the shifting yoke 46. Extending around the sprockets 43 and 50 is an endless chain 53 which also extends around a sprocket 54 on a stub shaft 55 journaled in one of the supporting posts 1. The chain 53 further extends around a tension adjusting sprocket 56 on a stub shaft 57 journaled in the same supporting post 1. The stub shaft 55 is rotated by means of an endless chain 58 which extends around a sprocket 59 on the stub shaft 55, and further extends around a sprocket 60 on the power shaft 8. Owing to the operation of the chains 58 and 53, the sprockets 43 and 50 are rotated simultaneously with the power shaft 8.

Pivotaly mounted on the shaft 18, adjacent the ends of the latter, are a pair of folding arms 61, each of which is provided with a vertically slotted enlargement 62 adjacent its lower end. Journaled in the folding arm 61, adjacent the lower ends of the latter, is a shaft 63 having what will be termed a lower carrier roll 64 fixedly mounted thereon. The shaft 63 is provided at one end with a sprocket 65 which is connected by means of an endless chain 66 with a sprocket 67 fixedly secured to the shaft 18. By means of the chain 66, the lower carrier roll 64 will be rotated simultaneously with the rotation of the upper carrier roll 19. Slidably and rotatably extending through the slots in the enlargements 62 are the end portions of a weight roller 68 which normally rests against the lower carrier roll 64. Pivotaly mounted on the shaft 21 are a pair of folding arms 69 which are similar in every respect to the folding arms 61. The folding arms 69 are provided with a lower carrier roll 70 similar to the carrier roll 64, and with a weight roll 71 similar to the weight roll 68. The carrier roll 70 is mounted on a shaft 72 which is operated from the shaft 21 by means of a chain 73 similar to the chain 66. Preferably the folding arms 61 and 69 will be provided

at their upper ends with counter weights 74 although these counter weights may be dispensed with if desired. During the rotation of the shaft 41, the folding arms 61 are reciprocated by means of a pair of links 75 which are pivotally connected with the arms 61, and which are further pivotally connected with cranks 76 fixedly secured to the ends of the shaft 41. During the rotation of the shaft 48, the folding arms 69 are reciprocated by means of a pair of links 77 which are pivotally connected with the arms 69 and with a pair of cranks 78 fixedly secured to the ends of the shaft 48.

Mounted in any suitable manner is a tank 79 which is divided into a plurality of compartments, each being adapted to contain a liquid to be sprayed on the cloth during the treatment thereof. In the present instance three such compartments are shown, the compartments being designated by the numerals 80, 81 and 82 and being provided respectively with valved discharge pipes 83, 84 and 85 which are connected with a common conduit 86 which is extended above the horizontal plane of the chain 34. The conduit 86 is connected by means of a three-way coupling 87 with a spray pipe 88 which extends transversely across the apparatus between the vertical planes of the squeeze rolls 10 and 11 and upper carrier roll 22, and with a branch 89 which extends at a right angle to the spray pipe 88. Connected with the branch 89 is a spray pipe 90 which extends transversely across the apparatus between the vertical planes of the squeeze rolls 10 and 11 and the upper carrier roll 19. The coupling 87 is provided with a three-way valve 91 which is adapted to be rotated in order to establish communication between the conduit 86 and the spray pipe 88 and branch 89 selectively.

In the operation of the apparatus, a roll of cloth 92 is rotatably supported on standards or the like, such as 93, in proximity to the forward end of the apparatus. The cloth from the roll is threaded between the lower carrier roll 64 and weight roll 68, over the upper carrier roll 19, under the guide roller 42, between the combined feed and squeeze rolls 10 and 11, under the guide roller 49, over the upper carrier roll 22, and between the lower carrier roll 70 and weight roll 71. The squeeze roll 11 is properly adjusted to snugly grip the cloth between the same and the squeeze roll 10, after which the power shaft 8 is rotated in a counter-clockwise direction as viewed in Figure 1. Such rotation of the power shaft causes the cloth to be moved towards the left as viewed in Figures 1 and 4. During the counter-clockwise movement of the power shaft, the automatic clutch 32 causes the upper carrier roll 22 to rotate in a counter-clockwise direction by means of which any slack is prevented between the upper carrier roll 22 and the squeeze rolls 10

and 11. During this movement the automatic clutch 23 remains neutral whereby the upper carrier roll 19 serves as a drag on the cloth between the lower carrier roll 64 and squeeze rolls 10 and 11. The dragging action of the upper carrier roll 19 prevents any wrinkling of the cloth without the exertion of any appreciable tension thereon. During this movement the lower carrier roll 64 remains stationary, due to the operative connection between the lower carrier roll 64 and upper carrier roll 19. Owing to the operative connection between the lower carrier roll 70 and upper roll 22, the lower carrier roll 70 is rotated during the movement of the cloth towards the left as viewed in the drawing. During this operation, the shifting yoke 46 is manually moved to a position to disengage the clutch member 45 from the sprocket 43, while the shifting yoke 52 is moved to engage the clutch member 51 with the sprocket 50. Owing to the set positions of the shifting yokes 46 and 52, the shaft 48 will be rotated, while the shaft 41 remains stationary. The rotation of the shaft 48 causes a reciprocating movement of the folding arms 69, due to the links 77 connecting the same with the cranks 78 secured to the ends of the shaft 48. The reciprocating movement of the folding arms 69 about their pivots causes the cloth to be deposited in folds within the cloth receiving vat 5. During this movement, the folding arms 61 remain stationary. During the time that the cloth is moving towards the left as viewed in the drawings, the valve 91 is adjusted in the position shown in Figure 8 in order that the liquid within the conduit 86 may be discharged through the spray pipe 88 onto the cloth. During this operation, one of the valves for the discharge pipes 83, 84 and 85 is opened while the remaining valves are closed.

Although the operation of the apparatus is above described as passing the cloth under the guide rollers 42 and 49, the cloth may be passed over these rollers if so desired with substantially the same result. In the latter event, the cloth extends directly from the squeeze rolls to the upper carrier rolls on opposite sides thereof.

After all of the cloth which it is desired to treat has been fed into the apparatus, the direction of the power shaft 8 is reversed to rotate the same in a clockwise direction as viewed in Figures 1 and 4 of the drawings. The reversal of the direction of the power shaft causes the automatic clutch 23 to rotate the upper carrier roll 19, and at the same time the automatic clutch 32 breaks the driving connection for rotating the upper carrier roll 22. Upon the reversal of the direction of the power shaft 8, the positions of the shifting yokes 46 and 52 are reversed in order to provide for the rotation of the shaft 41 and to prevent rotation of the shaft

48. Upon the rotation of the shaft 41, the folding arms 61 are reciprocated about their pivots owing to the links 75 connecting the same with the cranks 76 secured to the shaft 41. The reciprocation of the folding arms 61 causes the cloth to be deposited in folds within the cloth receiving vat 6. During the movement of the cloth towards the right as viewed in the drawing, the valve 91 is shifted 5 to close the spray pipe 88 to the conduit 86 and to establish communication between the conduit 86 and branch 89 in order that the liquid in the conduit may be discharged onto the cloth through the spray pipe 90. As the 10 cloth moves towards the right, the liquid is squeezed therefrom by the rolls 10 and 11 and is deposited within a drip pan 94 disposed beneath the roll 10 and suitably supported by the beam 2. The cloth is run back 15 and forth through the apparatus as aforesaid a sufficient number of times to accomplish the result desired, the valves for the discharge pipes 83, 84 and 85 being opened and closed from time to time as necessary to provide for the application of the proper solution to the cloth through the spray pipes 20 88 and 90. The cloth receiving vats 5 and 6 are provided with valved discharge pipes 95 and 96 respectively in order that the liquid 25 collecting within the vats may be drawn off as desired.

It is thought that the many advantages of this invention will be readily apparent, and 30 although the preferred embodiment of the invention is as illustrated and described, it is to be understood the changes in the size, shape and arrangement of parts may be resorted to, so long as such changes fall within 35 the scope of the invention as defined in the appended claims.

What I claims is:

1. In an apparatus for bleaching fabric in full width, open form, a pair of reversibly 45 rotatable combined feed and squeeze rolls for the passage of the fabric therebetween in opposite direction selectively, a pair of carrier rolls disposed on opposite sides of the combined feed and squeeze rolls for the passage 50 of the fabric thereover, a folding arm adjacent each of said carrier rolls, a carrier roll carried at the lower end of each folding arm, means for spraying the fabric after the same passes the combined feed and squeeze rolls, 55 means for rotating the carrier roll over which the fabric passes after leaving the combined feed and squeeze rolls, means for reciprocating the folding arm adjacent the rotating carrier roll, means for rotating the carrier roll carried by the reciprocating folding arm, and a vat for receiving the fabric from the reciprocating folding arm.

2. In an apparatus for bleaching fabric in full width, open form, a pair of reversibly 60 rotatable combined feed and squeeze rolls for

the passage of the fabric therebetween in opposite directions selectively, a pair of carrier rolls disposed on opposite sides of the combined feed and squeeze rolls for the passage of the fabric thereover, a folding arm adjacent each of said carrier rolls, a carrier roll carried at the lower end of each folding arm, a pair of spray pipes located over the fabric on opposite sides of the combined feed and squeeze rolls, a liquor conduit leading to said pipes, a valve in the conduit for admitting liquor to the pipe under which the fabric passes after leaving the combined feed and squeeze rolls, means for rotating the carrier roll over which the fabric passes after leaving the squeeze roll, means for reciprocating the folding arm adjacent the rotating carrier roll, means for rotating the carrier roll carried by the reciprocating folding arm, and a vat for receiving the fabric from the reciprocating folding arm. 70

3. In an apparatus for bleaching fabric in full width, open form, a pair of reversibly rotatable combined feed and squeeze rolls for the passage of the fabric therebetween in opposite directions selectively, a pair of carrier rolls disposed on opposite sides of the combined feed and squeeze rolls for the passage of the fabric thereover, a folding arm adjacent each of said carrier rolls, a carrier roll carried at the lower end of each folding arm, a pair of spray pipes located over the fabric on opposite sides of the combined feed and squeeze rolls, a liquor conduit leading to said pipes, a valve in the conduit for admitting liquor to the pipe under which the fabric passes after leaving the squeeze rolls, a plurality of liquor tanks, each having a valved discharge pipe leading to said conduit, means for rotating the carrier roll over which the fabric passes after leaving the combined feed and squeeze rolls, means for reciprocating the folding arm adjacent the rotating carrier roll, and a vat for receiving the fabric from the reciprocating folding arm. 80

4. In an apparatus for bleaching fabric in full width, open form, a pair of reversibly rotatable combined feed and squeeze rolls for the passage of the fabric therebetween in opposite directions selectively, a pair of carrier rolls disposed on opposite sides of the combined feed and squeeze rolls for the passage of the fabric thereover, a folding arm adjacent each of said carrier rolls, a carrier roll carried at the lower end of each folding arm, means for spraying the fabric after the same passes the combined feed and squeeze rolls, a sprocket rotatably mounted with respect to each carrier roll, means for driving said sprocket from the combined feed and squeeze rolls, means for clutching the carrier roll over which the fabric passes after leaving the combined feed and squeeze rolls to the sprocket rotatably mounted with respect to said 90

carrier roll to provide for the rotation of the latter, means for reciprocating the folding arm adjacent the rotating carrier roll, means for rotating the carrier roll carried by the reciprocating folding arm, and a vat for receiving the fabric from the reciprocating folding arm.

5. In an apparatus for bleaching fabric in full width, open form, a pair of reversibly rotatable combined feed and squeeze rolls for the passage of the fabric therebetween in opposite directions selectively, a pair of carrier rolls disposed on opposite sides of the combined feed and squeeze rolls for the passage of the fabric thereover, a folding arm adjacent each of said carrier rolls, a carrier roll carried at the lower end of each folding arm, means for spraying the fabric after passing the combined feed and squeeze rolls, a sprocket rotatably mounted with respect to each carrier roll, means for driving said sprockets from the combined feed and squeeze rolls, an automatic clutch for each of said carrier rolls and the sprockets rotatably mounted with respect thereto, said clutches operating to rotate the carrier roll over which the fabric passes after leaving the combined feed and squeeze rolls, means for reciprocating the folding arm adjacent the rotating carrier roll, means for rotating the carrier roll carried by the reciprocating arm, and a vat for receiving the fabric from the reciprocating folding arm.

6. In an apparatus for bleaching fabric in full width, open form, a pair of reversibly rotatable combined feed and squeeze rolls for the passage of the fabric therebetween in opposite directions selectively, a pair of carrier rolls disposed on opposite sides of the squeeze rolls for the passage of the fabric thereover, a folding arm adjacent each of said carrier rolls, a carrier roll carried at the lower end of each folding arm, means for spraying the fabric after the same passes the combined feed and squeeze rolls, means for rotating the carrier rolls over which the fabric passes after leaving the combined feed and squeeze rolls, a pair of guide rolls interposed between the carrier rolls and combined feed and squeeze rolls, a pair of shafts on which said guide rolls freely revolve, means operatively connecting the guide roll shafts with the combined feed and squeeze rolls to provide for the rotation of the guide rolls, cranks carried by the guide roll shafts and operatively connected with the folding arms respectively to provide for the reciprocation of the folding arms upon the rotation of the guide roll shafts, means for breaking the operative connection selectively for rotating the guide roll shafts, and a vat for receiving the fabric from the reciprocating folding arms.

7. In an apparatus for bleaching fabric in full width, open form, a pair of reversibly

rotatable combined feed and squeeze rolls for the passage of the fabric therebetween in opposite directions selectively, a pair of upper carrier rolls disposed on opposite sides of the combined feed and squeeze rolls for the passage of the fabric thereover, a folding arm adjacent each of said carrier rolls, a lower carrier roll carried at the lower end of each folding arm, means for spraying the fabric after the same passes the combined feed and squeeze rolls, means for rotating the upper roll over which the fabric passes after leaving the squeeze rolls, a pair of chains operatively connecting each of the upper carrier rolls with a lower carrier roll to provide for the rotation of the upper and lower carrier rolls in unison, means for reciprocating the folding arm adjacent the rotating carrier roll, and a vat for receiving the fabric from the reciprocating folding arm.

8. In an apparatus for bleaching fabric in full width, open form, a pair of reversibly rotatable combined feed and squeeze rolls for the passage of the fabric therebetween in opposite directions selectively, a pair of carrier rolls disposed on opposite sides of the combined feed and squeeze rolls for the passage of the fabric thereover, a folding arm adjacent each of said carrier rolls, a carrier roll carried at the lower end of each folding arm, means for spraying the fabric after the same passes the combined feed and squeeze rolls, means for rotating the carrier roll over which the fabric passes after leaving the combined feed and squeeze rolls, means for reciprocating the folding arm adjacent the rotating carrier roll, means for rotating the carrier roll carried by the reciprocating folding arm, a weight roll carried by each folding arm for abutment with the carrier roll carried thereby, and a vat for receiving the fabric from the reciprocating folding arm.

9. In an apparatus for bleaching fabric in full width, open form, a pair of reversibly rotatable combined feed and squeeze rolls for the passage of the fabric therebetween in opposite directions selectively, a pair of carrier rolls disposed on opposite sides of the combined feed and squeeze rolls for the passage of the fabric thereover, a pair of folding arms pivotally mounted with respect to each carrier roll, a carrier roll carried by the lower ends of each pair of folding arms, a vertically movable weight roll carried by each pair of folding arms for abutment with the carrier roll carried thereby, means for spraying the fabric after passing the combined feed and squeeze rolls, means for rotating the carrier roll over which the fabric passes after leaving the combined feed and squeeze rolls, means for reciprocating the folding arms adjacent the rotating carrier roll, and a vat for receiving the fabric from the reciprocating folding arms.

10. In an apparatus for bleaching fabric in

full width, open form, a pair of reversibly rotatable combined feed and squeeze rolls for the passage of the fabric therebetween in opposite directions selectively, a pair of carrier rolls disposed on opposite sides of the combined feed and squeeze rolls for the passage of the fabric thereover, a folding arm adjacent each of said carrier rolls, means for spraying the fabric after the same passes the combined feed and squeeze rolls, means for rotating the carrier roll over which the fabric passes after leaving the combined feed and squeeze rolls, and means for reciprocating the folding arm adjacent the rotating carrier rolls.

In testimony whereof, I affix my signature hereto.
